F. H. ELWELL

SPARK PLUG CLEANER

Filed Sept. 7, 1920

Patented June 12, 1923.

1,458,691

UNITED STATES PATENT OFFICE.

FRANKLIN H. ELWELL, OF CHICAGO, ILLINOIS.

SPARK-PLUG CLEANER.

Application filed September 7, 1920. Serial No. 408,434.

To all whom it may concern:

Be it known that I, FRANKLIN H. ELWELL, a citizen of the United States, and a resident of the city of Chicago, in the county of 5 Cook and State of Illinois, have invented certain new and useful Improvements in Spark-Plug Cleaners, of which the following is a full, clear, and exact specification.

This invention relates to improvements in 10 spark plug cleaners heretofore consisting of a casing removably screwthreaded upon the external threads of a spark plug, forming a closed reservoir for a cleansing fluid and provided with a perforated plunger for the 15 passage of the cleansing fluid therethrough, to which plunger are secured bristles which are limited in use to the cleansing of the ground and central electrodes.

The prime object of my invention broadly 20 stated, is a spark plug cleaner adapted to removably socket in the housing for the insulator thereof, having an imperforate plunger to which bristles are secured and so arranged that they are adapted for removing 25 deposits of carbon and other foreign material from the surface of the insulator in its entirety and likewise incidentally cleansing the ground and central electrodes.

More specifically stated, the object of my 30 invention is a spark plug cleaner, the casing or body portion of which is adapted to surround and be projected to contact with the base of the insulator and provided with a plunger from which project metallic bristles 35 arranged in their operative position to surround the surface of and adapted to be projected to endwise contact with the base of the insulator, and on being reciprocated and oscillated, to cleanse the surface of the 40 insulator in its entirety of carbon deposits by a cutting and scraping action.

A further object of my invention is to have the brush of a spark plug cleaner so constructed that it is adapted to first cleanse 45 deposits from the ground terminal and thereafter be maintained from contact therewith during and throughout the operation of the cleaner for removing the carbon deposits from the surface of the insulator in its 50 entirety.

With these ends in view, my invention finds embodiment in certain features of novelty in the construction, combination and arrangement of parts by which the said objects 55 are attained, all as hereinafter fully described with reference to the accompany-

ing drawings and more particularly pointed out in the claims.

In said drawings,—

Fig. 1 is a perspective view of a spark 60 plug cleaner in which my invention finds its embodiment, with the brush therefor in its retracted position.

Fig. 2 is a similar view showing the brush 65 in its projected position.

Fig. 3 is a transverse section on the line 3—3 of Fig. 1.

Fig. 4 is a longitudinal section in which the cleaner and spark plug are shown on an 70 enlarged scale.

Fig. 5 is a similar view taken on the line 5—5 of Fig. 4.

Similar characters of reference indicate 75 the same parts in the several figures of the drawing.

The shell or body portion of the spark plug cleaner in which my invention finds embodiment, consists of a tube 6 open at both ends and of a diameter adapted to removably fit the inner wall of the housing 80 7 for the insulator 8 with sufficient closeness for its end edges to scrape from the walls of the housing carbon and other foreign materials deposited thereon and to surround the insulator and seat against the 85 outwardly curved surface of its base.

Confined within the body portion 6 is a plunger 9, the rod 10 of which terminates in a handle 11, the stroke of which rod is limited by means of a pin 12 secured to the 90 plunger and projecting through an elongated closed end slot 13, which not only limits the stroke of the plunger, but is sufficiently wider than the diameter of the pin 12 to permit a slight oscillation of the 95 plunger.

Secured to the inner end of the plunger by any suitable means, is a brush 14 constructed of flexible bristles 15 which are arranged lengthwise in the form of a circle, provided at one side with an opening providing for a longitudinal slot 16 in the brush formed by the bristles, the bristles being preferably beveled at the free ends to provide cutting edges 12^a.

Normally the diameter of the circle formed by the bristles is such that their ends will contact with and first remove carbon deposited on the rounded end or nose 17 of the insulator 8.

The shell 6 has therein a longitudinal slot 18 adapted to straddle the horizontal arm

19 of the ground terminal 20 for the spark plug, the length of the slot being such as to permit the end of the shell to seat against the base of the insulator, or after being inserted for a sufficient distance to seat against the converging walls of the housing 7 and that before being seated the horizontal member 19 may not be bent from contact with the inner end wall of the slot 18. In this connection it is proper to note that the purpose of the longitudinal opening 16 between the bristles is to prevent them from lateral contact with the ground terminal with sufficient force to bend or otherwise injure the ground terminal 20 of the spark plug, when oscillating the brushes.

When, for any reason, the use of the brush is to be limited to the cleansing of the surface of the insulator, the slot 16 is normally open at the outer end of the bristles and the slot 18 is aligned with the slot 13.

As shown in the drawings, however, the outer end of the slot is normally closed by lugs of solder 21 secured to the bristles forming the opposing walls of the slot 16, but preferably in practice by reverse bends 22 in said bristles, and in any number sufficient to form yielding opposing jaws frictionally gripping the horizontal arm 19 of the ground terminal during its passage between them and thereby scraping deposits of carbon therefrom.

Located on a line passing between opposing faces of these yielding scrapers is a pin 23 secured at one end to the shell 6 and projecting inwardly beyond the axis of the brush, which pin, when the brush is withdrawn to the limit of its backward stroke, projects between and holds the jaws 22 separated for receiving the ground terminal before and during the initial forward thrust of the brush, following which the pin passes thence into the open slot 16 and the jaws grip the ground terminal and operate to scrape the deposits of carbon therefrom.

As shown, the slot 18 is parallel with and at one side of the opening 16 in the bristles and its inner end is in open communication with a transverse slot 24 in the shell, with the result that, following the insertion of the shell to its seated position in the housing the ground terminal is caused to register with the opening between the cleaning jaws 22 on turning the shell until said terminal occupies the position shown in Fig. 4.

With the several parts in the position shown in Fig. 4 the operator then pushes on the handle 11 until the ground terminal is entered between the jaws 22, and the pin 23 has passed from between the jaws 22 into the slot 16, whereupon the jaws will yieldingly grip the ground terminal, with the result that if there is a deposit of carbon on the ground terminal, it will be scraped therefrom before the free ends of the bristles have

come in contact with the nose 17 of the insulator 8.

As the pushing upon the brush is continued and following the initial contact of its bristles with the nose of the insulator, the cutting edges of the bristles operate to sever and loosen carbon deposits wherever they may be on the surface of the insulator, so that, following this they are quickly and cleanly removed therefrom on oscillating the brush but very little.

While it is preferable to construct the bristles of the brush of steel wire, because of their flexibility and resistance to a compressive force otherwise tending to bend them out of shape, my invention includes any material capable of successful use in a spark plug cleaner for cleansing carbon deposits from the insulator of a spark plug, nor is my invention limited to the circular form in cross-section of the brush or of the body portion therefor.

Again it is to be noted that carbon deposits on the ground electrode seldom occur as compared with the frequency and the amount of its deposit upon the surface of the insulator and the surrounding wall of the housing therefor, and therefore that my invention is not to be confined to the use of a brush provided with means for removing carbon deposited on the electrodes of a spark plug when it is otherwise adapted for removing such deposits from the surface of the insulator, either with or without removing them from the surrounding walls of the housing therefor.

Having described my invention, what I claim and desire to secure by Letters Patent is:

1. A spark plug cleaner, provided with a brush the bristles of which are normally straight and arranged longitudinally in a hollow circular form and adapted to substantially surround and thereby adapted to remove deposits of carbon and other material from substantially the entire surface of the insulator for a spark plug.

2. A spark plug cleaner, provided with a brush the bristles of which are arranged in a hollow circular form, and are provided with an open slot at one side thereof adapted to receive and maintain from contact therewith the ground terminal of the spark plug.

3. A spark plug cleaner, provided with bristles arranged to form a circle, the length of which bristles substantially correspond with that of the surface of the insulator to be cleaned of carbon deposits, said bristles being beveled across their free ends to form cutting edges adapted to sever said deposits and accordingly facilitating their removal from the insulator.

4. A spark plug cleaner, provided with a brush the bristles of which extend longitudinally and substantially parallel, and are ar-

ranged in hollow circular form, the ends of said bristles being beveled outwardly across their free ends to provide cutting edges thereby adapted to both cut and scrape from 5 the surface of the insulator for a spark plug and in its entirety carbon and other foreign material deposited thereon.

5. A spark plug cleaner, comprising a hollow body, a plunger therein, and a reciprocating means therefor, a brush the bristles of which are substantially straight throughout their length, are secured to the end of the plunger in hollow circular form and thereby adapted to have lateral and end contact 15 with a spark plug insulator.

6. A spark plug cleaner comprising a hollow body provided with a longitudinal slot, a plunger, a brush secured to said plunger the bristles of which are arranged in hollow 20 circular form, a pin secured to the plunger projecting through said slot for limiting the stroke of the brush.

7. A spark plug cleaner, comprising a hollow body, a plunger longitudinally movable 25 in said body, a brush secured to said plunger, and means connected with the plunger for controlling the movement of the brush, said brush comprising bristles arranged longitudinally and in hollow circular form with 30 a slot in one side thereof.

8. A spark plug cleaner comprising a hollow body provided with a closed end longitudinal slot, a plunger confined therein, and having a pin projecting through said slot 35 whereby the longitudinal and oscillating movement of the plunger is accordingly limited, said body portion also provided with another longitudinal slot occupying a plane parallel with said first slot and open at the 40 end of the plunger, and with transverse slot opening adjacent the inner end of said open end slot, and whereby the end of the shell may pass the ground terminal of a spark

plug to its seated position in the vicinity of the base thereof and to alinement with the 45 closed slot.

9. A spark plug cleaner comprising an open end hollow body portion, having therein a longitudinal slot closed at both ends, a plunger working in said body portion provided with a pin projecting through said slot for limiting the operating movement of the plunger, a brush secured to the end of the plunger the bristles of which are arranged in the form of a hollow circle, provided at one side with an opening extending the length of the bristles, said body portion being provided with another open end slot and a transverse slot connecting therewith and adapted to straddle the ground terminal of a spark plug cleaner during the movement of the body portion to its seated position and for alining said terminal with the slotlike opening in the brush. 55

10. A spark plug cleaner comprising a hollow body portion, a plunger confined and working therein, a brush the bristles of which are arranged in hollow tubular form, provided with a longitudinal opening between the bristles at one side, said bristles being 70 provided adjacent their free ends with resilient gripping jaws adapted to scrape deposits of carbon from the ground terminal of a spark plug in its passage between them, and means by which the ends of the body portion may be moved inwardly beyond said 75 terminal and move said terminal to register between said jaws.

In witness whereof, I have hereunto set my hand and affixed my seal, this 3rd day of September, A. D. 1920. 80

FRANKLIN H. ELWELL. [L. S.]
